VEREINIGTE STAHLWERKE AKTIENGESELLSCHAFT, OF DUSSELDORF, GERMANY

METHOD OF AND APPARATUS FOR ROLLING TUBES FROM A HOLLOW BLOCK

Application filed February 6, 1928, Serial No. 252,375, and in Germany February 25, 1927.

It is known, for instance by my prior U. S. Patent No. 1,610,593, to make tubes from a hollow block by subjecting the latter to the action of a system of pairs of 5 rolls arranged about the hollow block at a certain distance from its axis, each pair of rolls acting with one roll from inside and with the other roll from outside said block upon the walls of the latter. The pairs of 10 rolls are of gradually increasing width and of adjustable working depth so that by the first pair of rolls a circumferential nick beginning adjacent the front end of the block is cut into the material of the hollow 15 block, which nick is gradually widened by the following pairs of rolls toward said end. The axes of said rolls are inclined to the axis of the hollow block and act thus not only in a deforming manner but like a worm 20 gearing in an advancing manner upon the block. The advance of the hollow block begins, however, with the beginning deformation only, and it is a serious drawback that the hollow block to be rolled must be 25 pushed into the rolls by means of any outer expedients. In this connection, a further difficulty arises from the fact that the rolls, on account of the inclined position of their 30 axes, are arranged on the outer and inner periphery of the hollow block along a helical line and can thus come in working engagement therewith in a successive way only.

The outer force, which pushes the hollow 35 block into the working rolls, must therefore be so strong that it overcomes the resistance of the first pair of rolls to such an extent that the hollow block comes into the working range of the second pair of rolls 40 for permitting the latter to participate in the action of advancing the hollow block and thereby avoiding any overload and breaking of the driving axle of the first pair of rolls.

45 The present invention provides improved means for overcoming said difficulty. According to the same, the working rolls are extended in the direction of the incoming hollow block, that is toward their inlet end, 50 and at these extensions made of such a

diameter that, in the position of the rolls required for the action of their working parts, said inlet extensions engage the hollow block from its outside and from its inside and at the rotation of the rolls advance the same and introduce it into the working part of the rolls. Said inlet extensions of the rolls are so determined that the hollow block, as soon as it arrives at the same, is simultaneously caught by all 55 the pairs of rolls. The advancing action of said roll extensions can be further increased by providing them each with one or more peripheral beads, which suitably have such a distance from the working part of the 60 rolls and from each other as corresponds to the pitch of the helical line, along which the pairs of rolls are arranged about the inner and outer periphery of the hollow 65 block.

70 Furthermore, the block advancing action of the rolls can still be increased by extending the rolls also beyond their working parts toward the outlet end thereof and so determining the diameters of said outlet 75 extensions that the hollow block drawn out to form the tube is engaged from outside and from inside by said outlet extensions.

The improved construction of the rolls with an extension at their outlet end permits also to overcome the danger of the 80 piece of material, that is separated from the hollow block by the nick produced by the first pair of rolls, being first turned over, instead of being directly drawn out, by the 85 action of the following pairs of rolls, which may occur particularly with a rather short length of said piece of material and with a rather deep nick produced. Said turned-over piece of material is then, of course, 90 firmly rolled upon the other material of the hollow block while the same is being drawn out by the action of the working rolls, but it produces dangerous flaws in the 95 walls of the tube which are thereby weakened at these places.

By providing, according to the invention, the roll with an incline or abutment behind its main deforming part with a cavity between both, that is, between said abutment 100

and said main deforming part, said draw-back last mentioned is easily overcome by the separated piece of material to be drawn out bearing then against said cavity and being prevented from turning over.

• The accompanying drawing illustrates how the invention can be put into practice.

Figs. 1 and 2 show, for a clear understanding of the distinction between the known art and the invention, two different 10 pairs of working rolls hitherto used, while

Figs. 3 and 4 illustrate the improved arrangement for putting the invention into practice.

15 The reference letters designate: A the main deforming part of the rolls, B the extension toward the inlet end thereof, C the extension toward the outlet end thereof, D the hollow block, E the incline or abutment behind the main deforming part of the rolls, 20 and F a bead on the inlet extension B of the roll.

What I claim, is:

25 1. In a method of rolling tubes from hollow blocks consisting in drawing-out the latter in substantially axial direction by the utilization of pairs of rolls acting both from inside and outside upon said block and of which the axes are inclined to the axis of the latter, engaging the hollow block by inlet extensions of said rolls prior to the main working parts of the latter acting thereon thereby advancing the block and introducing it into the main working parts 30 of the rolls.

35 2. In a method as specified in claim 1, engaging the hollow block by outlet extensions of said rolls after the action of the main working parts of the latter thereon, thereby increasing the advancing action of 40 the rolls.

45 3. In a method as specified in claim 1, preventing the piece of material, that is separated from the hollow block at the beginning of the rolling action, being turned over and rolled upon the other material.

50 4. In an apparatus for rolling tubes from hollow blocks, the combination with a roll having a main deforming part, of an extension on at least one end thereof engaging the hollow block during the rolling action of said main deforming part, said roll having at least one peripheral bead on an extension of said roll at the inlet end thereof.

55 5. In a construction as specified in claim 4, an incline or abutment behind the main working part of said roll with a cavity between said abutment and said main working part.

60 In testimony whereof I have hereunto set my hand.

MARTIN ROECKNER.
